UNITED STATES PATENT OFFICE.

IRVING C. WOODWARD, OF CHICAGO, ILLINOIS.

SHIRT-WAIST BELT.

1,079,624.

Specification of Letters Patent.

Patented Nov. 25, 1913.

Application filed November 10, 1910. Serial No. 591,728.

To all whom it may concern:

Be it known that I, IRVING C. WOODWARD, a citizen of the United States of America, and a resident of Chicago, county of Cook, State of Illinois, have invented certain new and useful Improvements in Shirt-Waist Belts, of which the following is a specification.

The main objects of this invention are to provide an improved, simple and inexpensive form of belt, particularly adapted to be used for retaining the lower part of a shirt-waist in place about the waist line; to provide a belt of this kind adapted to efficiently prevent the shirtwaist from working up from under the waistband of a skirt without requiring that either the belt or the waist be fastened to the skirt or to each other.

An illustrative embodiment of this invention is shown in the accompanying drawings, in which:

Figure 1 is a perspective view illustrating the manner of applying the belt. Fig. 2 is a detail in perspective of the belt. Fig. 3 is a detail illustrating the manner of securing the buckle to the belt. Fig. 4 is an enlarged transverse cross-section of the belt.

In the construction shown in the drawings, the belt comprises a strip of flexible fabric 1, such as strong cotton tape of webbing, being preferably non-elastic. One surface of the strip 1 is coated with a slightly adhesive and strongly cohesive material 2, preferably a compound of rubber, which is unvulcanized, so that it retains its stickiness permanently. This is preferably applied to the surface throughout the entire length of the strip. The coating does not soil an uncoated surface but offers great frictional resistance to sliding movement of the strip along the surface of a garment.

In making a belt, one end 3, of the strip is passed through the loop of a buckle 4 and folded upon itself with the coated sur-

faces inside. The adhesiveness of the coating is almost sufficient to retain the buckle in place under normal strains, and in addition to this adhesiveness, a single transverse row of stitching 5 is ample. The other end 6 of the tape is folded diagonally across one corner, with the coated surfaces opposed, the folded part being further secured by a row of stitching 7.

In use, the belt is passed about the waist of the wearer outside of the shirtwaist, and with the coated side 2 inward. The end 6 is passed through the buckle 4 and drawn up, to cause the belt to fit snugly. The skirt is put on after the belt is in place, and the waistband of the skirt hides the belt. The adhesive surface 2 resists relative movement of the shirtwaist and belt, and it is found in practice that the movements of the wearer's body do not cause the shirtwaist to work up from the waist line, and that the belt effectively accomplishes this end without being in any way fastened to the skirt.

Although but one specific embodiment of this invention is herein shown and described, it will be understood that numerous details of the construction shown may be altered or omitted without departing from the spirit of this invention, as defined by the following claim.

I claim:

A belt comprising a strip of fabric having a coating of unvulcanized rubber compound, said belt being adapted to have frictional engagement with the surface of a garment to resist the sliding or creeping movement of said garment and prevent its disarrangement from a certain normal position.

Signed at Chicago this 8th day of November, 1910.

IRVING C. WOODWARD.
